(57) CLAIM

The ornamental design for tights, as shown and described.

DESCRIPTION

FIG. 1 is a front view of tights showing my new design; FIG. 2 is a rear view thereof; FIG. 3 is a side view thereof; and, FIG. 4 is a partial enlarged side view of the tights shown in FIG. 1, providing an enlarged view of a fletch pattern on the tights. The broken lines illustrate portions of the tights that form no part of the claimed design. The line shading and the stippling indicate a contrast in appearance.
